UNITED STATES PATENT OFFICE.

CHARLES TRIBBY, OF WASHINGTON, DISTRICT OF COLUMBIA, ASSIGNOR
TO HIMSELF AND JACOB HOOVER, OF SAME PLACE.

IMPROVEMENT IN WATCH-CASE SPRINGS.

Specification forming part of Letters Patent No. 123,798, dated February 20, 1872.

To all whom it may concern:

Be it known that I, CHARLES TRIBBY, of Washington, in the county of Washington and District of Columbia, have invented a new and useful Improved Watch-Case Lifting-Spring; and I do hereby declare that the following is a full, clear, and exact description thereof, sufficient to enable those skilled in the art to which my invention appertains to make and use the same, reference being had to the accompanying drawing making part of this specification and to the letters and figures marked thereon.

The nature of my invention consists in making a watch-case lifting-spring of brass instead of steel; and also in the peculiar construction and arrangement of the spring, as hereinafter particularly described.

In the accompanying drawing, Figure 1 is a top view, partly in section, of a watch-case with my improved lifting-spring attached. Fig. 2 is a sectional view of the same taken in the line $x x$ of Fig. 1. Fig. 3 is a detached view of the spring.

The spring A is made of brass, either round or square, as may be desired. It is of equal thickness for the entire length, except at the end where it comes in contact with the cap, at which point it is somewhat thinner than the other portion. The greatest width of the

spring is not greater than that of the narrowest portion of the ordinary steel spring, so that the spring fits snugly in the groove which runs around the inside of the case, and is entirely out of the way of the movement and the catch which holds the cap when closed.

The spring is hardened by rolling, drawing, or hammering, the proper tempering being thus obtained. In order to give it sufficient play, it is bent or curved, as shown at $a^1 a^2 a^3$ in Figs. 2 and 3. The spring occupies about one-fourth of the groove on the inside of the case, and is held in place therein by a pin or screw passing through the case and bearing against the spring, instead of passing through it. The large end of the spring A rests against the large end of the spring which forms the catch for holding the cap when closed. The pin or screw B is placed about midway between the center and small end of the spring A.

What I claim as new, and desired to secure by Letters Patent, is—

The brass lifting-spring A, formed with the curves $a^1 a^2 a^3$, and held in place by the pin or screw B, placed in front of instead of passing through it, all as herein shown and described.

CHARLES TRIBBY.
